UNITED STATES PATENT OFFICE.

JOHN JAMES REED, OF LYONS, IOWA, ASSIGNOR OF ONE-HALF TO DANIEL B. SNYDER, OF SAME PLACE.

SASH-FASTENER.

SPECIFICATION forming part of Letters Patent No. 394,936, dated December 18, 1888.

Application filed September 12, 1888. Serial No. 285,216. (No model.)

To all whom it may concern:

Be it known that I, JOHN JAMES REED, a citizen of the United States, residing at Lyons, in the county of Clinton and State of Iowa, 5 have invented a new and useful Improvement in Window-Fastenings, of which the following is a specification.

My invention relates to improvements in window-fastenings; and it consists in certain 10 novel features, hereinafter described and claimed.

In the accompanying drawings, Figure 1 is a front view of a portion of a window provided with my improved fastener. Fig. 2 is 15 a plan view of the upper edge of the lower sash, showing the fastening applied thereto. Fig. 3 is a side view, partly broken away. Fig. 4 is a detail view of one of the blocks over which the bolts slide. Fig. 5 is a detail 20 view showing the grooved plate, which is secured to the front side of the sash, and the tongue on the casting, which is engaged by said plate.

Referring to the drawings by letter, A designates the lower sash and B the upper sash. The upper sash is provided in the front face of its side bar with a series of sockets or openings, C, which are adapted to be engaged by 25 one of the bolts of my fastener, as will be hereinafter set forth.

B' designates the window-frame, in the side of which is formed a series of sockets or openings, C', similar to the sockets C, which are engaged by one of the bolts of the fastener.

D designates a casting provided with the plate E and the barrels F, formed on the upper side of the plate E at right angles to each other. These barrels F are provided in their upper sides with the longitudinal slots G, 30 having the notches H in one of their sides at or near their outer ends. The fastening-bolts I J move in these barrels, and are provided with studs K, which play in the slots G, and are adapted to engage the notches H to hold 35 the bolts withdrawn, when so desired. The bolts rest on blocks L, which are inserted in the lower sides of the barrels F, and have semicircular grooves M in their upper sides, the bolts resting in said grooves.

40 N O designate springs, which are arranged

in the inner meeting ends of the barrels F, and bear against the walls of the same at one end, and have their opposite ends passed through loops or eyes P in the rear ends of the bolts I J, respectively. These 55 springs serve to keep the bolts normally projected, as will be readily understood, and when the bolts are withdrawn the springs are compressed, so that upon releasing the pressure on the bolts the springs will at once force 60 them outward and cause them to engage the sockets C C', and thereby hold the sashes at the desired place.

On the upper side of the barrels F, at the angle formed at the meeting ends of the same, 65 I provide the offset Q, which serves as a rest for the thumb of the operator when withdrawing the bolts. This offset is placed at an angle to the barrels, so that it will serve 70 equally well for each.

The device is secured on the upper edge of the lower sash by means of screws passed through perforations R in the base E, and is further braced and secured in this position by means of a plate, S, secured to the front side 75 of the upper bar of the sash, and having the groove T on its rear side, which is engaged by a tongue or rib, U, on the casting.

In operation the bolts I J engage the sockets C C', respectively, and thereby support 80 the sash and secure the same at any desired point. It will be readily seen that by my device I provide a double fastening for the window, so that the two sashes can be properly locked together at any desired point. The 85 upper sash can be lowered and the lower sash can be raised independently of each other and secured, and it is not necessary that either one should be at any particular height for the proper operation of the device.

The device is very simple and can be manufactured at a slight cost, so that it can be sold cheaply and thus brought within the reach of all.

An ordinary coiled spring can be placed in 95 rear of the bolts to project the same; but I prefer to use the springs shown in the drawings, in which the springs are coiled around shafts or rods V and have their ends extending upward, one end bearing against the end 100

of the barrel and the other end engaging the loop or eye in the inner end of the bolt.

Having thus described my invention, what I claim, and desire to secure by Letters Patent, 5 is—

1. The combination of the base-plate, the barrels erected thereon, the vertical projection Q, formed on the upper side of the angle formed by the meeting ends of the barrels 10 and arranged at an equal angle to both of the barrels, and the bolts sliding in the barrels, as specified.
2. The combination of the casting having the barrels arranged at right angles to each 15 other, the blocks L, arranged in said barrels and having longitudinal grooves in their up-

per sides, the bolts sliding in said grooves and having eyes or loops at their inner ends, the rods V, secured transversely in the inner ends of the barrels, and the springs coiled around 20 said rods and having one arm bearing against the inner end of the barrel and its other end passing through the eye of the bolt, as specified.

In testimony that I claim the foregoing as 25 my own I have hereto affixed my signature in presence of two witnesses.

JOHN JAMES REED.
